UNITED STATES PATENT OFFICE.

JOHN M. WALSH, OF BEAUMONT, TEXAS.

STREET-PAVEMENT.

No. 890,110.

Specification of Letters Patent.

Patented June 9, 1908.

Application filed December 24, 1906. Serial No. 342,361.

To all whom it may concern:

Be it known that I, JOHN M. WALSH, a citizen of the United States of America, residing at Beaumont, in the county of Jefferson, in 5 the State of Texas, have invented certain new and useful Improvements in Street Pavements, of which the following is a specification.

The object of this invention is to provide a 10 durable, waterproof, elastic and economical street pavement adapted to serve as a substitute for the more expensive asphalt and cement pavements.

This invention consists principally of a 15 composition for pavements comprising limestone, limestone dust and crude mineral oil such as that produced by the oil wells of Texas and Louisiana. This composition constitutes one or more layers in a composite pavement. The crude Texas oil has an asphalt base containing more or less acid, which it is believed unites with more or less of the lime contained in the limestone and forms a 20 binder which cements the ingredients together.

This invention also consists in a pavement comprising two layers composed of a mixture of limestone, limestone dust and crude Texas oil and intermediate filling of broken stone 25 between said layers.

In carrying out this invention, a sub-grade nine inches, more or less, below the grade of the pavement when finished, is formed along the street. This sub-grade is properly wheeled 30 and rolled with a heavy seven ton or other suitable roller. A foundation or bottom layer, five inches more or less in depth, after rolling, is laid along the grade thus formed. This layer is preferably composed of hard broken 35 stone of about two-inch gage, rolled for seven hours more or less with a seven ton or other suitable roller. A second layer composed of this plastic composition is placed on said bottom layer. This composition layer, which 40 may be one-half inch more or less in depth when the pavement is finished, comprises a mixture of limestone, limestone dust and crude Texas oil. The limestone is preferably in broken particles of about one-half inch 45 gage. The preferred proportions in bulk of the mineral matter are seventy-five per centum of the broken limestone and twenty-five per centum of the limestone dust and about fifteen gallons of the oil are added to a 50 cubic yard of the mineral mixture. The oil

is mixed raw with the limestone by means of hand shovels in a common mortar box or other suitable implements and no heating is necessary. This composition is spread without rolling over the bottom layer to the depth required to form a second layer of the desired thickness when the pavement is finished. 60 This second layer constitutes a waterproof cement which shuts out water from below. A third layer composed of hard broken stone, 65 preferably of about two-inch gage is then placed on top of the second layer, sufficient in quantity to form a finished layer of two inches more or less in depth. A fourth layer is then formed over the third layer. This 70 fourth layer comprises hard limestone, preferably of one-inch gage, and sufficient in quantity to form a finished layer one inch more or less in depth. The whole pavement thus far laid is then rolled for six hours, more 75 or less, with a seven-ton or other suitable roller. A top layer composed of the improved composition aforesaid comprising a mixture of limestone, limestone dust and crude Texas oil is then laid over said partially 80 completed pavement to a depth required to form a finished layer of one inch more or less in thickness and this layer is rolled with a seven ton or other roller for seven hours more or less. Then dry hard limestone dust 85 is scattered and brushed with a hand broom or otherwise over the pavement formed as aforesaid, in quantity sufficient to merely cover the top thereof.

This pavement furnishes a good foothold 90 for horses and is fine for automobile travel as the wheels do not slide readily thereon and it will not cut the tires. It is strong, economical to construct and water-proof. The lower layer of this plastic composition excludes water from below and the top layer thereof excludes water from above. Repairs 95 may be easily made by filling with limestone of say one-inch gage any holes that may form and tamping on top thereof the composition 100 of limestone, limestone dust and heavy crude oil hereinbefore described.

This pavement is well adapted for county roads, and in such case may be constructed substantially the same as for city streets but 105 of less depth.

This pavement may be used as a foundation for brick or block pavements and it will turn water as well as any cement or stone concrete and will not crack or sink.

I claim as my invention—

1. A composition for pavements comprising a mixture of limestone, limestone dust and crude mineral oil of the Texas type.
- 5 2. A pavement comprising a plurality of layers of different materials, one of said layers comprising a mixture of limestone, limestone dust and crude mineral oil of the Texas type.
- 10 3. A pavement comprising two layers each composed of a mixture of limestone, limestone dust and crude Texas oil, and an intermediate filling of broken stone disposed between the layers aforesaid.
- 15 4. A pavement comprising two layers each composed of a mixture of limestone, limestone dust and crude Texas oil, and an intermediate filling composed in part of ordinary broken stone and in part of broken limestone disposed between the layers aforesaid.
- 20 5. A pavement comprising a foundation layer, a layer disposed thereon composed of limestone, limestone dust and crude Texas oil a superposed layer of hard broken stone

of determinate gage, a layer composed of 25 hard limestone of smaller gage and a layer composed of a mixture of limestone, limestone dust and crude oil.

6. A pavement comprising a foundation layer composed of hard stone of about two 30 inch gage, a layer disposed thereon composed of limestone, limestone dust and crude Texas oil, a layer composed of hard stone of about two-inch gage, a layer composed of hard limestone of smaller gage and a top layer 35 composed of a plastic mixture of limestone, limestone dust and crude Texas oil.

7. A pavement comprising a filling composed in part of hard broken stone of determinate gage and in part of broken limestone 40 rolled together and a top layer composed of a mixture of limestone, limestone dust and crude oil of the Texas type united with said filling.

JOHN M. WALSH.
